UNITED STATES PATENT OFFICE

CARL F. GOUDY, OF FLUSHING, NEW YORK, ASSIGNOR TO PACENT ELECTRIC COMPANY, INC., OF NEW YORK, N. Y., A CORPORATION OF NEW YORK

ELECTRIC PHONOGRAPH REPRODUCER

Application filed June 14, 1929. Serial No. 270,784.

This invention relates to electric phonographs and particularly to the mounting and arrangement of the reproducer or so-called pickup unit.

5 The objects of the invention are to provide a balanced mounting for the pickup, which will enable the latter to properly follow the record groove, which will support the unit in a convenient position for changing of needles or the like, and clear of the record, so as to avoid any possibility of scratching the record; and to accomplish the foregoing in a neat attractive structure suited to high class phonograph instruments.

15 The desired objects are attained by certain novel features of construction, combinations and relations of parts as hereinafter described and particularly claimed.

The drawing accompanying and forming 20 part of the specification illustrates one practical commercial embodiment of the invention, it being understood that the structure may be modified as regards this particular disclosure without departure from the true 25 spirit and broad scope of the invention.

Fig. 1 is a broken side elevation of the complete unit illustrating in broken lines the pivotal mounting by which the pickup unit can be thrown back for replacing needles 30 and showing how at this time the arm is independently supported to prevent the unit or the arm from dropping down on the record; Fig. 2 is a broken plan view of the device; Fig. 3 is a detached perspective view of the 35 pivotal mounting bracket; Fig. 4 is an enlarged cross-sectional view of the same as on line 4-4, Fig. 1; Fig. 5 is a cross-sectional view as on substantially the plane of line 5-5 of Fig. 1.

40 The casing or shell of the pickup unit is indicated at 7, the same being shown as of generally rectangular shape, housing the pickup mechanism which carries a needle or stylus 8 for engagement with the phonograph record. This stylus is removably clamped by a screw 9 having an operating head exposed at the front of the casing.

45 Secured on the back of the casing 7 is a special bracket shown as having a flat base 50 portion 10 riveted or otherwise suitably se-

cured to the case at 11 and as having a rearwardly projecting substantially rectangular neck portion 12 with screw seats 13 in opposite sides of the same to receive pivot screws 14. These screws are indicated as extending 55 in through pivot openings 15 in the side flanges 16 of the channel bar 17, the top of this channel bar being cut out at the end at 18 to enable the bracket to swing to the upper position shown in the broken lines, Fig. 1. 60 The side flanges of the channel bar are shown cut on a downward forward incline at 19 to act as stops engaging the back of the bracket at 20 to hold the unit at the desired incline relative to the record surface. 65

The pickup unit is yieldingly retained in its operative position in the present disclosure by spring detents in the form of the balls 21 retained in protruding relation by flanges 22 in the ends of a transverse passage 3 in 70 the neck of the bracket, the spring 24 forcing these balls apart so that they will snap into interlocking relation with seats or openings 25, Fig. 1, in the side flanges. These spring detents thus normally retain the pickup unit in the operative relation shown in Fig. 1, but they yield readily to permit the unit to be thrown back into the upraised position, for substitution of needles or the like. In the latter position, the neck of the 75 bracket rests against the edge 26 of the cut-out top portion of the channel bar, which latter therefore acts as a stop to limit the upward swinging movement and to support the unit in the thrown-back relation. 80

85 The unit supporting arm is pivoted for both lateral and vertical swinging movements, in the present disclosure, by means of a vertical pivot tube 27 journalled in a post or pedestal 28 and carrying at its upper end 90 a head or yoke in the form of a plate 29 having upwardly angled lugs or flanges 30 disposed within the flanges 16 of the channel bar, horizontal pivot screws 31 being extended through openings in said side flanges 95 into screw seats provided in said lugs to hinge the supporting arm on a horizontal axis.

To prevent the free end of the supporting arm from dropping down when the pickup unit is raised, the side lugs 30 of the pivot 100

head are indicated as extended upward and turned inward at 32 to form rests located forwardly of the horizontal pivots 31, Fig. 1 and adapted to engage the underside of the 5 channel bar, when that bar tilts downward below the normally operative position. These rests therefore provide a simple means for supporting the unit in the raised relation and enable the unit to be left in this condition without danger of scratching the records.

To counter-balance the weight of the unit to an extent, the rearward end of the supporting arm, to the right of the horizontal pivots in Figs. 1 and 2 is weighted by a block 15 33 shown as having its center of mass below the axis of the horizontal pivots and as having an angular neck portion 34 fitting in between the side flanges of the channel bar and secured thereby rivets or other suitable 20 fastenings 35.

The base or supporting pedestal is indicated as of hollow construction to receive the wires 36, which are lead up through the vertical pivot sleeve 27 and inside the channel 25 of the supporting arm and the recess 37 in the underside of the bracket, to the pickup unit.

The inverted channel provides a particularly rigid and strong supporting arm, and 30 at the same time it is relatively inexpensive, since stock channel material may be used. The several parts, that is the pickup at one end, the counterweight at the opposite end and the pivot mounting intermediate the ends 35 may all be connected with the side flanges of the channel, leaving the intermediate portion clear for passage of the electric connections. The unit and the counterweight are fitted to the opposite ends of the channel arm, so as to 40 present on the whole a harmonious attractive appearance.

What is claimed is:

1. In apparatus of the character disclosed, 45 an inverted channel arm having the top portion of the same cut out at one end, a phonograph pickup unit having a neck portion disposed between the side flanges of the channel arm at the said cutout end, pivot means extending through the side flanges and through 50 said neck portion of the unit, a counter-weight secured between the side flanges of the channel at the opposite end of the same and pivot means engaged with the side 55 flanges of the channel between the ends of the same.

2. In apparatus of the character disclosed, 60 a phonograph pickup unit, a vertically pivoting and horizontally swinging supporting arm for said unit, said unit having a horizontal pivotal mounting on the arm enabling the unit to be swung upwardly into an inoperative position and a rest positioned to support the vertically pivoting arm when the unit is swung up into said inoperative relation.

3. In apparatus of the character disclosed, a vertically pivoted support having upstanding lugs and an inverted channel arm having its side flanges embracing said upstanding lugs, pivot means engaged with said lugs 70 and flanges, one of said lugs extending up within the inverted channel to form a rest for supporting the same and a pickup unit mounted on one end of said channel arm.

4. In apparatus of the character disclosed, 75 a pivoted supporting arm of channel cross-section, a phonograph pickup unit having a neck portion swivelled to the side flanges of said channel supporting arm and a weight member having a neck portion positioned between and secured to said side flanges. 80

5. In apparatus of the character disclosed, 85 a pivoted supporting arm of channel cross-section, a phonograph pickup unit having a neck portion swivelled to the side flanges of said channel supporting arm, said neck portion of the unit operating between the side flanges and spring detent means between said side flanges and neck portion.

6. In apparatus of the character disclosed, 90 a pivoted supporting arm of channel cross-section, a phonograph pickup unit having a neck portion swivelled to the side flanges of said channel supporting arm, said neck portion of the unit being disposed between the 95 side flanges and the body portion of the channel arm being cut back from the ends of the side flanges to provide clearance for said neck portion and to provide a stop engageable by the swivelled neck portion of 100 the pickup unit to limit the swivelling movement of and to support the unit in upturned relation.

7. In a device of the character disclosed, a 105 pedestal, a head journalled on said pedestal and having upstanding lugs, an inverted channel arm engaged over said lugs, pivot means extending through the lugs and the side flanges of the channel arm, a counter-balance weight secured between the side flanges 110 at one end of the channel arm, a casing for a pickup unit and a bracket fixed on the back of said casing and having an extending neck portion pivotally engaged between the side flanges at the opposite end of the 115 channel arm.

8. In a device of the character disclosed, 120 a pedestal, a head journalled on said pedestal and having upstanding lugs, an inverted channel arm engaged over said lugs, pivot means extending through the lugs and the side flanges of the channel arm, a counter-balance weight secured between the side flanges at one end of the channel arm, a casing for a pickup unit and a bracket fixed 125 on the back of said casing and having an extending neck portion pivotally engaged between the side flanges at the opposite end of the channel arm, the top of the channel arm at said end being removed between the 130

side flanges to receive the neck of the bracket and form a stop for engagement by said neck portion.

9. In a device of the character disclosed, an inverted channel arm, a pivot head located within the hollow of said channel arm, said arm having its side flanges pivoted horizontally to said head and said head having a rest extending up beneath the top of the channel arm to form a support for the arm limiting down swinging movement of the arm and a pickup unit carried by the end of said channel arm.

10. In apparatus of the character disclosed, a phonograph pickup unit, a swinging supporting arm for the same, said arm being of inverted channel construction with dependent side flanges joined by a top wall, said top wall at one end of the arm being cut back from the ends of the side flanges and said pickup unit having a neck portion swivelled to the arm and operating in the cutaway portion of the arm between the side flanges.

11. In apparatus of the character disclosed, a phonograph pickup unit, a swinging supporting arm for the same, said arm being of inverted channel construction with dependent side flanges joined by a top wall, said top wall at one end of the arm being cut back from the ends of the side flanges, said pickup unit having a neck portion swivelled to the arm and operating in the cutaway portion of the arm between the side flanges and mounting means for the opposite end portion of the arm, said mounting means being engaged with said dependent side flanges of the arm.

12. In a device of the character disclosed, the combination of a pickup unit having a neck portion and a length of channel bar having side flanges and a portion of the bar connecting said side flanges being cutaway at one end of the bar to receive the neck portion of the unit, means for securing said neck portion of the unit in position between the side flanges, means engaged with the side flanges at a point removed from the unit for pivotally supporting the channel bar, said channel bar being positioned by said supporting means in inverted relation with the channel of the same facing downward and wiring for the unit disposed in said downwardly faced channel, the neck of the unit between the side flanges having a portion in line with the channel to accommodate said wiring.

13. As a new article of manufacture, a supporting arm for a pickup unit, comprising a length of channel bar having side flanges connected by a web portion and said web portion being cut back from the ends of the side flanges at one end of the bar to accommodate the neck portion of the pickup

unit, with the projecting end portions of the side portions adapted to provide pivotal mounting elements.

In testimony whereof I affix my signature.

CARL F. GOUDY.
